CLAIM

The ornamental design for a smart ring, as shown and described.

DESCRIPTION

FIG. 1 is a front perspective view of a smart ring, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a cross-sectional view of the smart ring taken through line 9-9 in FIG. 3 and along the direction of the arrows at the two ends of the line 9-9; and,

FIG. 10 is an enlarged detail view of area 10 in FIG. 1. The dashed broken lines in FIG. 3 represent a cut line only and form no part of the claimed design.

(Continued)

The dash-short-dash broken lines encircling portions of the smart ring in FIG. 1 and illustrated in an enlarged view in FIG. 10 form no part of the claimed design.
